UNITED STATES PATENT OFFICE.

HARRY E. SMALLBONE, OF BUFFALO, NEW YORK, ASSIGNOR TO DOMESTIC SEWING MACHINE CO., INC., OF BUFFALO, NEW YORK, A CORPORATION OF NEW YORK.

SEWING-MACHINE.

1,262,114.

Specification of Letters Patent. Patented Apr. 9, 1918.

Application filed May 9, 1917. Serial No. 167,555.

To all whom it may concern:

Be it known that I, HARRY E. SMALLBONE, a citizen of the United States, residing at Buffalo, county of Erie, State of New York, have invented a certain new and useful Improvement in Sewing-Machines, and declare the following to be a full, clear, and exact description of the same, such as will enable others skilled in the art to which it pertains to make and use the same, reference being had to the accompanying drawings, which form a part of this specification.

One of the inconvenient features of the ordinary sewing machine is the cover or plate which must be removed whenever access is desired to the shuttle. The present invention has for its object to produce a simple and novel arrangement by means of which the aforesaid cover or plate may be placed in position and removed quickly and conveniently and, when in position, be firmly held.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a top plan view of the shuttle-end of the bed or table of a sewing machine arranged in accordance with a preferred embodiment of my invention;

Fig. 2 is a section on line 2—2 of Fig. 1;

Fig. 3 is a section taken on line 3—3 of Fig. 1;

Fig. 4 is a section taken on line 4—4 of Fig. 1; and

Fig. 5 is a bottom plan view of the detachable cover or plate removed from the machine.

Referring to the drawings, 1 represents the bed of a sewing machine having a central section cut out of the end thereof to provide an opening, 2, through which access may be had to the shuttle. In the sewing machines with which I am familiar this opening is closed by a plate having a tightly fitting dovetailed joint with the bed, making it difficult for the user to remove the plate. In accordance with my invention, I so construct the parts that the cover or plate 3, while firmly held in place, may be lifted out upon the release of a simple catch. To

this end the bed of the machine is provided with depressed seats, 4 or 5, at opposite sides of the opening 2, the plate resting on these seats and being of such thickness that its top surface is flush with the top surface of the bed. At the inner edge of the plate are one or more fingers, 6, projecting from the under side of the plate in position to hook under the adjacent portion of the bed when the plate is placed in position. On the under side of the plate is a swinging arm, 7, hinged at one end and having at its other end a downwardly projecting hook, 8, so positioned that it will extend downwardly through a passage, 9, cut through the seat 5 and engage with the under side of the bed at the edge of this passage; the passage being wide enough to permit the hook to swing from a locking position to an unlocked position. A finger hole, 10, is formed in the plate near the outer edge thereof; and the finger hole and the member 7 are so positioned relatively to each other that the latter overlaps the finger hole more or less when in its locked position. In order to insure that the cover will be positioned accurately, it may be provided with a pair of downwardly projecting pins, 11 and 12, the first of which is adapted to enter a hole in the seat 4 while the other extends down through the passage 9 and engages with one of the bounding edges thereof.

While the parts may take various shapes and forms, those illustrated have been found to be very satisfactory. Thus the two fingers or lips, 6, form part of a V-shaped plate, 13, bent at the apex into the form of a housing, 14, in which is placed a spring, 15, bearing against one edge of the arm or lever 7, either directly, or through a plunger, 16, and tending to hold this arm in its locking position. The member 7 may be made out of sheet metal having at one end a keyhole slot, 17, through the small end of which the hinge pin, 18, extends; while at the other end of the plate is a slot, 19, in the form of an arc of a circle having its center at the axis of the pin 18; a holding and guide pin, 20, extending through the slot into the plate; the slot 19 having a branch, 21, opening out through one edge of the member 7; and there being a detachable screw or stop, 22, on the member 7 in a position to engage the guide member 20 and normally prevent it from moving out of the 110

main portion of the slot 19. Furthermore, one of the edges of the hook 8, as indicated at 23, or the corresponding bounding edge of the passage 9, as indicated at 24, or both, 5 are preferably made inclined so that the hook will automatically be pressed back against the tension of the holding spring when the plate 3 is placed in position and pressed downwardly; the spring moving the 10 hook into its locking position after it has traveled down far enough.

It will be seen that when the cover plate is in position it is firmly held and, when it is desired to remove the same, all that is required is that the finger be inserted in the 15 finger hole 10 to press the locking arm or lever laterally, whereupon the cover plate may be lifted up by means of the finger that is used to unlatch it.

20 While I have illustrated and described with particularity only a single preferred form of my invention, I do not desire to be limited to the exact structural details thus illustrated and described; but intend to cover 25 all forms and arrangements which come within the terms employed in the definitions of my invention constituting the appended claims.

I claim:

30 1. In a sewing machine, a bed having a section removed from one end to provide an opening to give access to the shuttle, a cover for said opening, bearing seats for the cover arranged at the sides of said opening, a lip 35 or finger on the cover adapted to project underneath a part of the bed, said cover having a pin adapted to enter a guide opening in one of the bearing seats, and a catch device adapted to hold the cover on said 40 seats.

2. In a sewing machine, a bed having a section removed from one end to provide an opening to give access to the shuttle, a cover for said opening, bearing seats for the cover arranged at the sides of said opening, a lip 45 or finger on the cover adapted to project underneath a part of the bed, said cover having a pin adapted to enter a guide opening in one of the bearing seats, the other bearing seat having a portion cut away to form a 50 passage, and a catch device secured to the under side of the cover and adapted to project downwardly through said passage and

interlock with the bed at one edge of the passage.

55

3. In a sewing machine, a bed having a section removed from one end to provide an opening to give access to the shuttle, a cover for said opening, bearing seats for the cover arranged at the sides of said opening, a lip 60 or finger on the cover adapted to project underneath a part of the bed, an arm hinged on the under side of the cover and having at one end a hook, said bed having a part adapted to be engaged by said hook, and a 65 spring acting on said hook in a direction to force it into engagement with the coöperating part on the bed when the cover is placed on said seats.

4. In a sewing machine, a bed having a 70 section removed from one end to provide an opening to give access to the shuttle, a cover for said opening, bearing seats for the cover arranged at the sides of said opening, a lip 75 or finger on the cover adapted to project underneath a part of the bed, an arm hinged on the under side of the cover and having at one end a hook, said bed having a part adapted to be engaged by said hook, and a 80 spring acting on said hook in a direction to force it into engagement with the coöperating part on the bed when the cover is placed on said seats, said cover having a finger hole 85 extending through the same and exposing a portion of said arm.

85

5. In a sewing machine, a bed having a section removed from one end to provide an opening to give access to the shuttle, a cover for said opening, bearing seats for the cover arranged at the sides of said opening, a lip 90 or finger on the cover adapted to project underneath a part of the bed, an arm hinged on the under side of the cover and having at one end a hook, said bed having a part adapted to be engaged by said hook, and a 95 spring acting on said hook in a direction to force it into engagement with the coöperating part on the bed when the cover is placed on said seats, said cover having therein a 100 finger hole so placed that the said arm normally projects partly across the same so as to be wedged into a cover releasing position upon the insertion of a finger into said hole.

In testimony whereof I sign this specification.

HARRY E. SMALLBONE.
